UNITED STATES PATENT OFFICE.

FRANK SIEGRIST, OF COOPERSBURG, PENNSYLVANIA.

DIRECTION INDICATOR.

Application filed November 26, 1923, Serial No. 677,102. Renewed August 19, 1925.

To all whom it may concern:

Be it known that I, FRANK SIEGRIST, a citizen of the United States, residing at Coopersburg, in the county of Lehigh and State of Pennsylvania, have invented new and useful Improvements in Direction Indicators, of which the following is a specification.

This invention relates to direction indicators particularly designed for use on motor vehicles, and an object of the invention is to provide a direction indicator which is simple in construction, easily operated and which co-operates with the spot-light or cowl lights of a motor vehicle, utilizing the background of the light or lamp in the day time to render the signal visible and the light rays from the lamp at night to render the signal readily visible.

Another object of this invention is to provide a direction indicator as specified which may be readily and quickly attached to spot-lights of existing construction without requiring alterations to the spot-light, and one which may be quickly and easily operated to clearly set forth the direction about to be taken by the vehicle equipped with the device, and thereby acquainting approaching motorists of the intentions of the driver of the vehicle equipped with the indicator and consequently avoiding serious accidents or collision, and also permitting the acquainting of pedestrians or traffic policemen of the direction to be taken by the equipped vehicle.

Other objects of the invention will appear in the following detail description, and in the accompanying drawings wherein:

Figure 1 is a front elevation of the improved direction indicator showing it mounted in position.

Figure 2 is a side elevation of the direction indicator showing it mounted in position.

Figure 3 is a top plan of the indicator showing it detached.

Figure 4 is a detail section on the line 4-4 of Figure 3.

Figure 5 is a detail view of a part of the direction indicator structure.

Referring more particularly to the drawings, the improved direction indicator comprises an attaching structure 1 which includes a circle attaching band or ring 2.

The band or ring 2 has suitable angled clips 3 attached thereto or formed thereon at

spaced points which are adapted to engage over the rear portion 4 of a spot-light 5 of any approved construction. One of the clips 3 has a set-screw 6 adjustably carried thereby for clamping engagement with the back 4 of the spot-light to securely hold the attaching structure in place. A bracket 7 is attached to the attaching ring 2 and a bearing structure 8 is carried by the bracket 7 and forms a support 4 for the shaft 9. The shaft 9 has a head 10 on its inner end which is transversely drilled to receive the end of the rod 11 therethrough and a set-screw 13 is provided for adjustably connecting the rod 11 to the head 10. The rod 11 is substantially U-shaped in plan and it extends across the back and side of the spot-light 5 as clearly shown in Figure 2 of the drawings. The front end 14 of the rod 11 is flattened and a direction indicating arrow 15 is riveted or otherwise suitably attached thereto. As clearly shown in Figure 1 of the drawings, the arrow 15 extends across the front of the light or lamp 5 so that in the day time the lens and the reflector of the light will serve as a background to increase the visibility of the arrow and at night the light rays from the lamp will serve as a background for increasing the visibility of the arrow. The shaft 9 has a thumb-button 17 thereon by means of which the shaft may be rotated for moving the rod 11 and consequently moving the arrow either into a vertical position or into a horizontal position with the head 18 of the arrow pointing either to the right or to the left to indicate the direction to be taken by the vehicle equipped with the spot-light.

Owing to the fact that the travel of the vehicle and the construction therewith which cause the rod 11 to fall into a horizontal position when it is moved into a vertical position to indicate that the vehicle is going straight ahead and to prevent such accidental falling movement, a spring plate 18 is supported from the bracket 7 and it has a transversely extending notched upper end 19 which notch receives the rod 11 and holds it in its upright position and holds the arrow 15 in its upright or vertical position. The bracket 7 is positioned so as to form a support or abutment against which the rod 11 engages for holding the arrow 15 in horizontal position.

While in the drawings and in the foregoing description the direction indicator has

been illustrated and described as applied to a spot-light of any approved type, such as used on motor vehicles, it is to be understood that the indicator may be arranged for use 5 in connection with cowl, tail or even headlights, without departing from the spirit of this invention.

It is, of course, to be understood that the invention may be constructed in various 10 other manners and the parts associated in different relations and, therefore, I do not desire to be limited in any manner except as set forth in the claims hereunto appended.

What I claim is:

- 14 1. The combination with a spot-light for a vehicle, of a direction indicator comprising an attaching structure for detachable engagement with the spot-light, an arrow carrying rod supported from said bracket and 20 extending partially about the spot-light, and an arrow carried by said rod and movable in front of the lens of the light, and a thumb-button connected to said rod for moving the rod and arrow.
- 25 2. The combination with a spot-light for a vehicle, of a direction indicator comprising an attaching structure for detachable engagement with the spot-light, an arrow carrying rod supported from said bracket and 30 extending partially about the spot-light, an arrow carried by said rod and movable in front of the lens of the light, a thumb-button connected to said rod for moving the rod

and arrow, and means for holding said arrow in certain adjusted positions.

35

3. The combination with a spot-light for a vehicle, of a direction indicator comprising an attaching structure for detachable engagement with the spot-light, an arrow carrying rod supported from said bracket and 40 extending partially about the spot-light, an arrow carried by said rod and movable in front of the lens of the light, a shaft bracket carried by said attaching structure, a shaft rockably carried by said bracket and connected to said rod for moving the rod in an are about the center of the shaft as an axis.

45

4. The combination with a spot-light for a vehicle, of a direction indicator comprising an attaching structure for detachable engagement with the spot-light, an arrow carrying rod supported from said bracket and 50 extending partially about the spot-light, an arrow carried by said rod and movable in front of the lens of the light, a shaft bracket carried by said attaching structure, a shaft rockably carried by said bracket and connected to said rod for moving the rod in an are about the center of the shaft as an axis, 55 said bracket adapted to engage said rod to limit the movement of the rod, and means carried by said bracket for holding the rod and arrow in vertical positions.

60

In testimony whereof I affix my signature.

FRANK SIEGRIST.
